US00D592618S

(12) **United States Design Patent**
Lewis, II et al.

(10) **Patent No.:** US D592,618 S
(45) **Date of Patent:** ** May 19, 2009

(54) **ELECTRONIC EQUIPMENT CABINET**

(75) Inventors: **Richard Evans Lewis, II**, Austin, TX (US); **James I. Lawrence**, Georgetown, TX (US); **Eugene Vicknair**, Santa Clara, CA (US); **Victor Lazzaro**, Discovery Bay, CA (US)

(73) Assignee: **Chatsworth Products, Inc.**, Westlake Village, CA (US)

(**) Term: **14 Years**

(21) Appl. No.: **29/320,824**

(22) Filed: **Jul. 3, 2008**

Related U.S. Application Data

(60) Continuation of application No. 29/304,739, filed on Mar. 6, 2008, now Pat. No. Des. 584,252, which is a division of application No. 29/248,104, filed on Jul. 28, 2006, now abandoned.

(57) **CLAIM**

The ornamental design for an electronic equipment cabinet, as shown and described.

DESCRIPTION

FIG. 1 is a perspective view of the design for an electronic equipment cabinet in accordance with a first preferred embodiment of the present invention;

FIG. 2 is a front elevational view of the electronic equipment cabinet of FIG. 1;

FIG. 3 is a left elevational view of the electronic equipment cabinet of FIG. 1;

FIG. 4 is a right elevational view of the electronic equipment cabinet of FIG. 1;

FIG. 5 is a top plan view of the electronic equipment cabinet of FIG. 1;

FIG. 6 is a perspective view of the design for an electronic equipment cabinet in accordance with a second preferred embodiment of the present invention;

FIG. 7 is a front elevational view of the electronic equipment cabinet of FIG. 6;

FIG. 8 is a left elevational view of the electronic equipment cabinet of FIG. 6;

FIG. 9 is a right elevational view of the electronic equipment cabinet of FIG. 6; and,

FIG. 10 is a top plan view of the electronic equipment cabinet of FIG. 6.

The broken lines depict portions of the electronic equipment cabinet that form no part of the claimed design.
